SPARK PLUG TESTING DEVICE

Howard H. Vogel and Lawrence R. Lentz, Toledo,
Ohio, assignors to Champion Spark Plug Com-
pany, Toledo, Ohio, a corporation of Delaware

Application January 14, 1950, Serial No. 7,246

Term of patent 14 years

(Cl. D26—1)

To all whom it may concern:

Be it known that we, Howard H. Vogel and Lawrence R. Lentz, citizens of the United States and residents of Toledo, county of Lucas, State of Ohio, have invented a new, original, and ornamental Design for a Spark Plug Testing Device, of which the following is a specification, reference being had to the accompanying drawings, forming a part thereof.

In the drawings, Fig. 1 is a perspective view of a spark plug testing device embodying our new design; Fig. 2 is a front elevational view thereof; Figs. 3 and 4 are side views; Fig. 5 is a top plan view; and Fig. 6 is a rear elevational view.

The dominant features of our design reside in the portions shown in full lines.

We claim:

The ornamental design for a spark plug testing device, substantially as shown and described.

HOWARD H. VOGEL.
LAWRENCE R. LENTZ.
